The ornamental design for a vehicle roof rack obstacle detection sensor, as shown and described.

DESCRIPTION

FIG. 1 is a perspective view of the vehicle roof rack obstacle detection sensor showing my new design;

FIG. 2 is a side view of the vehicle roof rack obstacle detection sensor shown in FIG. 1;

FIG. 3 is another side view of the vehicle roof rack obstacle detection sensor shown in FIG. 1;

FIG. 4 is a top view of the vehicle roof rack obstacle detection sensor shown in FIG. 1;

FIG. 5 is a bottom view of the vehicle roof rack obstacle detection sensor shown in FIG. 1;

FIG. 6 is a front view of the vehicle roof rack obstacle detection sensor shown in FIG. 1; and,

FIG. 7 is a rear view of the vehicle roof rack obstacle detection sensor shown in FIG. 1.
